CHARLES E. SMITH, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,113,255.

Specification of Letters Patent.

Patented Oct. 13, 1914.

Application filed July 2, 1913. Serial No. 776,903.

To all whom it may concern:

Be it known that I, CHARLES E. SMITH, a subject of the King of England, residing in New York city, in the county of New 5 York and State of New York, have invented certain new and useful improvements in Type-Writing Machines, of which the following is a specification.

My invention relates to mechanism for 10 causing the typewriter carriage to jump forward a predetermined uniform distance or number of letter spaces, each time a special or multiple-space key is actuated, for the purpose of spacing between sentences, paragraph indentation, rapid feed of the carriage, tabulator work, etc.

A feature of the invention is the provision of a plurality of special devices controlled by separate multiple-space keys and 20 operable independently to control the throw of the carriage, each device being preferably adjustable to vary the distance the carriage will jump when the corresponding key is operated. By the use of separate 25 jump-controlling devices, the adaptability of the machine for various uses is increased. For example, one of the keys may be used for spacing between sentences, the device controlled thereby being set for 30 three, four, or any desired number of letter spaces. A second key may be used for paragraph indentations, the device controlled by said key being adapted to effect 35 a suitable spacing for this purpose, as, for example, the distance of eight or ten letter spaces. Either one or both of these super-spacing devices may, in addition, be used for effecting a rapid run of the carriage in various other kinds of work. Thus, by re-

40 peatedly depressing the key which is set for paragraph indentation, the carriage may be quickly advanced a great distance. This movement will be much more rapid, and accomplished with less effort than by the use 45 of the ordinary single-space key. One or more of the multiple-space keys may also in some cases be used in tabulator work. Thus one key may be used alone for moving the carriage from one column position to another, or additional keys may be selectively used to bring the carriage to different po-

sitions in a column, the particular key operated at any time depending on the position of the first digit or character in the particular line and column to be written. 55

When either of the special keys is operated, the spring-driven carriage is released from the escapement mechanism and put under the control of a special super-spacing device, which permits the carriage to space 60 or jump a fixed distance; and when said key is released the carriage is withdrawn from the control of the super-spacing device and restored to the control of the ordinary letter-feeding mechanism. Each special key 65 controls a separate super-spacing member, and the latter is preferably adjustable to vary the distance the carriage jumps.

Normally idle racks are mounted on the machine frame, to be independently caused 70 by the separate special-spacing keys to shift into locking connection with super-spacing devices or stop-plates on the carriage, each stop-plate permitting the carriage to jump or advance a fixed distance. Each special 75 space key also operates to release the carriage and permit it to jump. The stop-plates are mounted on a guide on the carriage, and each stop-plate carries a stop-pin which extends into a slot in said guide, 80 the pin being adjustable on the stop-plate to vary the distance the stop-plate can move relatively to the carriage. One of the rack bars may also be formed with rack teeth to carry the column stops of the ordinary 85 tabulating mechanism, said stops being adjustable longitudinally of the rack, and also settable into and out of position to coöperate with the ordinary tabulating counter-stop on the carriage. 90

The same key may, if desired, be used alternatively as a tabulator key or as a multiple-space key for sentence spacing, etc., and in such a case, in order to silence the super-spacing devices, the tooth or detent on 95 said stop-plate with which the rack engages, is movable out of operative position.

The multiple-space keys may be used separately for different purposes, as, for example, sentence spacing, paragraph indentation, spacing between columns in tabulator work, etc., each stop being adjustable 100

to cause the carriage to jump any desired distance, depending on the purpose for which it is used.

Other features and advantages will hereinafter appear.

In the accompanying drawings which illustrate one form of my invention, Figure 1 is a rear elevation view showing a portion of an Underwood typewriting machine 10 with my invention applied thereto. Fig. 2 is a view similar to the right-hand portion of Fig. 1, but showing one of the slidable stop-plates in operated position. Fig. 3 is a fragmentary sectional elevation showing 15 means for swinging the rack bars, and other details of the invention, the lower rack bar being in operated position, and a column stop set to operative position. Fig. 4 shows a guide plate on which the slidable stop- 20 plates or jump-controlling devices are mounted. Fig. 5 is a perspective view of one of the stop-plates. Fig. 6 is a sectional elevation view of the machine. Fig. 7 is a perspective view showing means for releasing 25 the escapement rack and operating the swinging rack bars. Fig. 8 is a view similar to Fig. 6, but with one of the swinging racks in operated position.

Type-keys 1 are mounted on key levers 2 30 fulcrumed at 3 and operable through bell cranks 4 to move the type-bars 5 upwardly to printing position in front of the platen 6. The platen is shiftably mounted on a carriage 7 driven in letter-feed direction by a 35 spring motor 8 connected through a belt 9 to the carriage, the carriage being guided on a rear guide rail 10 and a front guide rail, not shown. The letter-feed travel of the carriage is controlled by escapement mechanism 40 comprising escapement dogs 11 coöperating with an escapement wheel 12 driven by an escapement pinion 13 which runs in mesh with a rack 14 on the carriage. Each type-bar has a shoulder 15 which, when the type- 45 bar is actuated, moves a universal bar 16 forwardly and operates the dogs 11, the reciprocation of said dogs effecting a letter-feed movement of the carriage in the usual way. The escapement rack 14 is connected 50 to the carriage by a swinging frame 17 which permits the rack to be lifted from the escapement pinion 13 so that the carriage may move independently of the escapement mechanism.

In order that the carriage may be moved forwardly a multiple letter-space distance by the single operation of a space key, the following mechanism is provided. A rock-shaft 18 mounted on the machine frame, 60 preferably in rear of the platen and parallel therewith, has secured thereto upwardly and rearwardly extending arms 19 to which is fixed a rack bar 20 adapted to be swung forwardly to engage a tooth 21 on a stop-plate 65 22 slidably mounted on the carriage, to per-

mit a limited travel of the carriage while said plate is locked to the rack bar. The rack bar 20 is swung inwardly by means of a multiple-space key 23 on a lever 24 fulcrumed on the rod 3 and connected through 70 a link 25 to an arm 26 fixed to the rock shaft 18, so that when the key 23 is depressed the rack 20 will be swung inwardly to engage the tooth 21. The key 23 also operates to lift the escapement rack 14 to permit the multiple letter-space movement of the carriage. The escapement rack is lifted by a roller 27 on a rock plate 28, over which extends an arm 29 fixed to the rock shaft 18. 75

The slidable stop-plate 22 is mounted on a guide plate 30 fixed to the carriage frame and having shouldered screws 31 extending through slots 32 in the stop-plate 22, thereby permitting the stop plate to move relatively to the carriage in a direction opposite to the forward travel of the carriage, or, in other words, when the stop-plate is held by the rack 20, the carriage is permitted to jump forwardly a limited distance. The distance the carriage is permitted to move is determined by a stop pin 33 which may be set in any one of a series of openings 34 in the plate 22, said stop pin extending into a slot 35 in the plate 30, so that when the stop-plate 22 is connected, to the rack 20, the travel of the carriage is limited by the end of the slot 35 being brought up against the stop pin 33. 80

When the space key 23 is depressed and the rack 20 thereby swung inwardly to engage the tooth 21 on the stop-plate 22, the escapement rack 14 is also lifted to free the carriage so that the latter is moved forwardly by its spring 8 a distance determined by the position of the adjustable stop pin 33. 100 When the key 23 is released, it is returned by its spring 36, the rack 20 swings out and releases the stop-plate 22, and the escapement rack 14 reengages its pinion to lock the carriage. The plate 22, being released, is 105 returned by a spring 37.

The teeth on the rack 20 are preferably at letter-space distances apart so that the tooth 21 may engage the rack 20 while the carriage is at any normal position of rest 115 throughout its range of travel. The openings 34 for the stop pin 33 are also preferably letter-space distances apart, as measured in the direction of the carriage travel, so that the stop pin may be adjusted to effect 120 a movement of the carriage equal to any desired number of letter spaces within the limits of adjustment of the stop pin.

In order to provide for jump movements or multiple letter-space movements of the 125 carriage through different distances, and independently controlled by separate keys, additional mechanism is provided which is in many respects similar to that already described. This additional mechanism may 130

comprise a swinging rack bar 38 located below the rack 20 and swinging about the same axis. The rack bar 38 is carried by arms 39 and 40 connected respectively to sleeves 41 and 42 loosely mounted on the rock shaft 18, and is preferably provided with an upper rack or set of rack teeth 38^a coöperating with a stop-plate 48, and a lower rack or set of rack teeth 38^b forming part of the tabulating mechanism.

Secured to the sleeve 41 is an arm 43 connected through a link 44 and lever 45 to a finger key 46. The sleeve 41 carries at its inner end an arm 47 extending over the rock plate 28 to lift the escapement rack when the key 46 is depressed. When the rack bar 38 is swung inwardly by depressing the key 46, it is locked to the sliding stop-plate 48 similar to the plate 22, by means of a tooth 49 on the plate 48. The tooth 49, instead of being secured directly to the plate 48, is preferably on a lever 50 pivoted to the plate to permit the tooth 49 to be moved upwardly out of position to co-operate with the rack teeth 38^a so that the rack bar 38 may be used as a tabulator rack bar independently of the stop-plate 48. The lever 50 is provided with notches 51, engageable by a spring detent 52 to hold the lever in either position of adjustment.

The plate 48 has a slot-and-pin connection with the plate 39 as described in connection with the plate 22. It is also provided with an adjustable stop pin 33^a and openings 34^a, said stop pin working in a slot 35^a in the plate 39. A return spring 37^a is provided for the plate 48. When the stop or tooth 49 is set to operative position, as shown in the drawings, the operation of the lower sliding stop-plate 48 and the rack 38 is the same as that already described in connection with the plate 22 and rack 20. By setting the two stop pins 33 and 33^a in different positions relative to their stop plates, the multiple space keys 23 and 46 may be used for moving the carriage through different distances. For example, the stop pin 33 is shown in Fig. 1 set in position to effect the movement of the carriage through five letter-spaces; the key 23 controlling said stop might therefore be used for the usual spacing between sentences. The lower stop pin 33^a (as shown) being set to effect the movement of the carriage through ten letter-spaces, the key 46 might be used for indenting at the beginning of paragraphs. Either key might also be used in billing and other work for rapidly moving the carriage through a considerable distance by depressing the key a number of times in succession. The multiple-space mechanism is also adapted for various other combinations and uses. The key 46 may also be used as a tabulator key to cause the carriage to run forwardly to

predetermined fixed positions; the rack bar 38 in this instance forming part of a tabulator mechanism, and for this purpose being provided with a lower rack or set of rack teeth 38^b for holding in adjusted position column stops 53 slidably mounted on a rod 54 parallel with the rock shaft 18. The stops 53 have teeth 55 to interlock with the rack teeth 38^b when the stops are swung forwardly to operative position, as shown in Fig. 3. Each stop 53 also has a forward extension 56 movable into the path of a counter-stop 57 on the carriage, so that when a column stop 53 is locked to the rack 38^b, and the rack swung forwardly by operating the key 46, the travel of the carriage will be limited by the counter-stop 57 striking the column stop, as shown in Fig. 3.

When it is desired to use the key 46 as a tabulator key, the tooth 49 on the sliding stop plate 48 is moved to inoperative position, and one or more of the column stops 53 are adjusted along the rack bar and locked thereto. Each of the column stops 53 may be provided with a pointer or indicator 58 which, when the stop is in operative position, lies over a scale 59 extending along the rack bar 38, to indicate the position of the stop. The operation of the key 46, will now release the carriage and permit it to move forwardly until arrested by the first column stop in the path of the counter-stop on the carriage. When the key 46 is thus used as a tabulator key, the key 23 may be used for spacing between sentences, etc.

Although I have shown two swinging racks which may be separately operated, the invention is not limited to two. The adjustable stops on the carriage may also be used in tabulator work, the multiple-space keys being operable to move the carriage from one column to another, and the stops being adjusted for different spacings so that the carriage will move from one column to a position in the next column, corresponding to the multiple-space key which is operated.

Although I have shown two racks 38^a and 38^b arranged respectively to coöperate with the multiple-space stop plate and to adjustably hold the column stops, my invention is not limited to the use of two racks for this purpose.

Variations may be resorted to within the scope of the invention, and portions of the improvements may be used without others.

Having thus described my invention, I claim:

1. In a typewriting machine, the combination with a carriage, a rack bar and a co-operating member, of means to bring said rack bar and said member into engagement in any position of travel of the carriage, said carriage having a limited movement

- 5 relatively to said member and in the direction of the carriage travel, and means to move the carriage through said limited movement when said member and rack bar are in engagement.
- 10 2. In a typewriting machine, the combination with a carriage, of a rack, a stop on the carriage, said carriage movable relatively to said stop in the direction of the carriage travel, and means to bring said stop and rack into engagement in any letter-space of the carriage, and to cause the carriage to move relatively to said stop in letter-spacing direction.
- 15 3. In a typewriting machine, the combination with a carriage, of an escapement mechanism controlling the movement of the carriage, a stop on the machine frame, a counter-stop on the carriage to co-act with said stop on the frame in any position of the carriage, said carriage having a limited movement relatively to said stop in the direction of the carriage travel, and means to bring said stops together and release the carriage to permit it to travel while said stops are together.
- 20 4. In a typewriting machine, the combination with a carriage, of an escapement mechanism controlling the movement of the carriage, a stop on the machine frame, a counter-stop on the carriage to co-act with said stop on the frame in any position of the carriage, said carriage having a limited movement relatively to said stop in the direction of the carriage travel, means to bring said stops together and release the carriage to permit it to travel while said stops are together, and means to automatically return the counter-stop to its initial position on the carriage when released from the carriage stop.
- 25 5. In a typewriting machine, the combination with a carriage, of a rack co-extensive with the carriage travel, a stop on the carriage, said carriage being movable relatively to said stop in the direction of its travel, a key, means operated thereby to bring said rack into engagement with the stop in any position of travel of the carriage, mechanism controlling the travel of the carriage and actuated by said key to release the carriage, and means to advance the carriage a distance determined by the relative movement of the carriage and stop.
- 30 6. In a typewriting machine, the combination with a carriage and an escapement mechanism controlling the letter-feed travel of the carriage, of a swinging rack bar, a member on the carriage, said carriage having a limited movement longitudinally of said member, and key-operated means for swinging the rack into locking engagement with said member in any position of travel of the carriage and for releasing the carriage from the escapement mechanism.
- 35 7. In a typewriting machine, the combination with a carriage and escapement mechanism controlling the letter-feed movement of the carriage, of a slidable stop-plate on the carriage, a stop on said plate, a key connected to swing said rack and engage said stop-plate in any position of travel of said carriage, means operated by said key to release the carriage from the escapement mechanism and permit a limited movement of the carriage while said stop-plate is held by the rack, and means to return said plate to its initial position on the carriage when released from the rack.
- 40 8. In a typewriting machine, the combination with a carriage, of a stop-plate slidably mounted on the carriage, a stop on said plate adjustable to vary the movement of said plate on the carriage, and means co-operating with said stop-plate to hold it and thereby permit a limited movement of the carriage.
- 45 9. In a typewriting machine, the combination with a carriage, of a plate slidably mounted thereon, means to drive the carriage, and a holding device co-operating with said plate and operable in any position in the travel of the carriage, to limit said travel.
- 50 10. In a typewriting machine, the combination of a carriage, a rack upon the machine frame extending in the direction of the carriage travel, letter-feed mechanism controlling the carriage travel, a stop, means to bring said stop and rack into engagement in any position of the carriage in its travel independently of the position to which the carriage has been brought by its letter-feed travel, and means to cause a predetermined movement of the carriage whenever said stop and rack are brought into engagement.
- 55 11. In a typewriting machine, the combination with a rack bar having teeth at letter-space intervals, of a traveling carriage, a stop-plate on the carriage movable longitudinally thereof a predetermined distance, escapement mechanism, and a key connected to swing said rack to engage said stop-plate in any position of the carriage in its travel and to release the escapement mechanism.
- 60 12. In a typewriting machine, the combination with a carriage, of a guide plate fixed to the carriage frame, a stop-plate having a slot and pin connection with the fixed plate, said stop-plate being provided with a series of openings, a stop pin adapted to be placed in any one of said openings and extending into a slot formed in said guide plate, a tooth on said stop-plate, and a rack movable into and out of position to engage said tooth.
- 65 13. In a typewriting machine, the combination with a carriage, of a plurality of stops slidably mounted on the carriage,

- racks independently movable into position to coöperate with said stops, and keys operatively connected to said racks.
14. In a typewriting machine, the combination with a carriage, of stops mounted thereon for movement in the direction of the carriage travel, adjustable means to limit the movement of each stop to a predetermined number of letter-space intervals, swinging racks coöperating with the respective stops, and keys connected to independently operate said racks.
15. In a typewriting machine, the combination with a carriage, of a rack bar, column stops adjustable along said bar, a counter-stop on the carriage, a key connected to swing said rack bar and bring said column stops into the path of the counter-stop, said column stops being movable to inoperative position, and a stop slidable on the carriage and adjustable into and out of position to coöperate with said rack bar whereby a letter-feed movement of the carriage through a predetermined number of letter-space intervals may be effected by the operation of said key.
16. In a typewriting machine, the combination with a carriage, of a rack bar having a plurality of racks, a column stop adjustable along the rack bar and held in adjusted position by one of said racks, a counter-stop on the carriage, a key connected to the rack bar to move it into position to bring the column stop into the path of the counter-stop, whereby the carriage may be brought to a predetermined position, and a stop slidable on the carriage and located in position to be engaged by the other said rack when said rack bar is operated whereby the carriage may be moved a distance determined by the relative movement of the slidable stop and carriage, said slidable stop and column stop being independently adjustable into and out of operative position whereby said key may be selectively used either as a tabulator key or a multiple-space key for feeding the carriage through a predetermined number of letter-space intervals.
17. In a typewriting machine, the combination with a carriage, of a motor to drive the carriage, an escapement mechanism controlling the feed of the carriage, a plurality of swinging racks, coöperating stops on the carriage, keys to independently operate said racks into position to engage the respective stops on the carriage, and a device for releasing the carriage from the escapement mechanism when either of said keys is operated.
18. In a typewriting machine, the combination with a carriage, of stops thereon, swinging rack frames mounted on the machine frame and comprising racks, and keys connected to selectively swing said racks into position to coöperate with said stops.
19. In a typewriting machine, the combination with a carriage, of a rock shaft journaled on the machine frame and extending in the direction of the carriage travel, a rack frame fixed to the rock shaft, a sleeve journaled on said rock shaft, a rack frame fixed to said sleeve, rock arms secured respectively to said rock shaft and sleeve, key levers, links connecting them to said rock arms, and stop mechanism on the carriage.
20. In a typewriting machine, the combination with a carriage, of stops thereon, a rock shaft journaled on the machine frame and extending in the direction of the carriage travel, a rack frame fixed to the rock shaft and comprising a rack movable into position to coöperate with one of said stops, a sleeve journaled on said rock shaft, a rack frame fixed to said sleeve and comprising a rack movable into position to coöperate with another of said stops, rock arms secured respectively to said rock shaft and sleeve, key levers, and links connecting them to said rock arms.
21. In a typewriting machine, the combination of a carriage, a movement limiting member thereon, said carriage being capable of movement relatively to said member in spacing, and means on the machine frame co-extensive with the length of carriage travel, to engage said member in any position of travel of said carriage for limited spacing movement by said carriage.
22. In a typewriting machine, the combination of a carriage, a member on said carriage stationary during a limited portion of the carriage travel in spacing, and means on the machine frame co-extensive with the length of carriage travel, to engage said member in any position of travel of said carriage for limited spacing movement by said carriage.
23. In a typewriting machine, the combination of a carriage, a member on said carriage stationary during a limited portion of the carriage travel in spacing, and means on the machine frame co-extensive with the length of carriage travel, to engage said member in any position of travel of said carriage, whereby said carriage may move through limited spacing distances wherever desired in a continuous line.
24. In a typewriting machine, the combination of a carriage, means upon said carriage stationary during a portion of the carriage travel, whereby at any point in the carriage travel said means may be engaged by the machine frame to afford limited movement of said carriage from that position of engagement, and key-operated means to effect such engagement and permit said limited movement.

25. In a typewriting machine having a carriage and an escapement therefor, the combination of a space-jumping control member on said carriage, means on the machine frame to engage said member in any position of travel of said carriage, means to release the carriage from the escapement, means to actuate said engaging means, and a finger key to operate both said releasing and actuating means simultaneously, whereby the carriage may jump through a predetermined number of spaces.
26. In a typewriting machine, the combination of a carriage, a member thereon for affording variable limited movement of the carriage relatively to said member in space jumping, and means on the machine frame to engage said member in any position of travel of said carriage for said variable limited space-jumping movement, whereby said carriage may travel through variable limited distances wherever desired in a continuous line.
27. In a typewriting machine, the combination of a carriage, a member on said carriage stationary during a variable limited portion of the carriage travel in spacing, and means on the machine frame to engage said member in any position of travel of said carriage for variable limited spacing movement.
28. In a typewriting machine, the combination of a carriage, a member on said carriage stationary during a variable limited portion of the carriage travel in spacing, and means on the machine frame to engage said member in any position of travel of said carriage, whereby said carriage may move through variable limited spacing distances wherever desired in a continuous line.
29. In a typewriting machine, the combination of a carriage, a device upon said carriage stationary during a portion of the carriage travel, a member upon the machine frame by which at any point in the carriage travel, said carriage device may be engaged, to afford variable limited movement of said carriage from that position of engagement, and key-operated means to effect such engagement and permit said variable limited movement.
30. In a typewriting machine having a carriage, the combination of a member on the machine frame co-extensive with the length of carriage travel, a column stop adjustable along said member, a counter-stop on said carriage, a space-jumping control member on said carriage stationary during a limited portion of the carriage travel, and means on the machine frame to effect engagement either between said column and counter stops for tabulating, or between said space-jumping control member and the machine frame to permit the carriage to jump through predetermined spacing distances.
31. In a typewriting machine having a carriage and escapement mechanism therefor, the combination of a member on the machine frame co-extensive with the length of carriage travel, column stops adjustable along said member and movable into and out of operative position, a counter-stop on said carriage, a space-jumping control member on said carriage movable into and out of operative position, said space-jumping control member, when operative, being stationary on said carriage during a limited portion of the carriage travel, and a finger key to release the carriage from said escapement mechanism and effect engagement either between a column stop and said counter-stop for tabulating, if a column stop is in operative position, or between said space-jumping control member and the machine frame to permit the carriage to jump through predetermined spacing distances, if said space-jumping control member is in operative position.

CHARLES E. SMITH.
